DOOR LATCH AND LOCK

Harry T. Smith, Flint, Mich.

Application October 14, 1942, Serial No. 462,007

2 Claims. (Cl. 70—37)

This invention relates to door locks and more particularly to a lock adapted for sliding doors.

An object of this invention is to provide a lock for sliding doors which embodies a pivoted bolt and an improved means for locking the bolt.

Another object of this invention is to provide an improved door bolt which is very simple in construction and which can be constructed in the sides of a sliding door.

A further object of this invention is to provide an improved door bolt which embodies a minimum of parts so that it can be made at small cost and will not get out of order, the bolt being gravity actuated to locking position and all springs being eliminated.

A further object of this invention is to provide a bolt of this kind which may be locked or unlocked on one side of the door without the use of a key, and which may only be locked or unlocked on the other side of the door by use of a key.

The invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation of a sliding door latch and lock constructed according to an embodiment of this invention, showing the device mounted in a door which is fragmentarily shown and also showing in vertical section a keeper mounted in an opposed door.

Figure 2 is a sectional view taken on the line 2—2 of Figure 1.

Figure 3 is a sectional view taken on the line 3—3 of Figure 2, with the two doors in closed position.

Figure 4 is a sectional view taken on the line 4—4 of Figure 3.

Figure 5 is a front elevation of the escutcheon or guide member.

Figure 6 is a fragmentary sectional view taken on the line 6—6 of Figure 1.

Figure 7 is a front elevation of the keeper for the bolt.

Figure 8 is a sectional view taken on the line 8—8 of Figure 3.

Figure 9 is a detail side elevation of a modified form of latch and bolt.

Figure 10 is a longitudinal section of the device in released position, and

Figure 11 is a sectional view taken on the line 11—11 of Figure 9.

Referring to the drawings, and first to Figures 1 to 8 inclusive, the numerals 10 and 11 designate generally a pair of sliding doors which are slidably mounted in the opposite sides of a door opening and which embody a construction similar to that set forth in my co-pending application Serial Number 454,324, filed August 10, 1942.

The door 10 has countersunk in the opposite sides thereof a pair of cup-shaped housings 12 and 13. The housing 12 comprises an inner circular wall 14, a cylindrical outwardly extending flange 15 and an annular flange 16 which is adapted to engage against the adjacent face of the door 10. The housing 13 opens outwardly in the opposite direction from the housing 12 and comprises an inner circular wall 17, a cylindrical side wall 18 and an annular flange 19.

An elongated door bolt 20 is disposed between the two spaced apart inner walls 14 and 17 of the two housings 12 and 13 and is formed at its outer end with a hook 21. The door 10 has countersunk in the outer vertical edge 22 thereof an escutcheon or guide member, generally designated as 23. The guide member 23 includes an inner vertical wall 24, opposite side walls 25, upper and lower walls 26 and a front wall 27. The escutcheon 23 is adapted to be secured in an opening or recess 28 formed in the forward or outer edge of the door 10 by fastening devices 29. The outer or forward wall 27 of the escutcheon 23 is provided with an elongated opening 30 through which the keeper 50 is adapted to loosely engage. The inner wall 24 is also formed with a similar opening to the opening 30, and the inner end of the bolt 20 extends medially between the two housings 12 and 13, as shown in Figure 2. A longitudinally arcuate bolt operator or handle 31 is disposed within the open side of the housing 12, and a similar longitudinally arcuate handle or bolt operator 32 is disposed within the open side of the housing 13.

A square shaft 33 is secured at the opposite ends thereof to the lower ends of the two handles or operators 31 and 32 and is also secured to the inner end of the bolt 20. The operator 31 is formed with a reduced stud or bearing member 34 which rotatably engages in an opening 35 formed in the inner wall 14. The operator 32 at the lower end thereof is also formed with a reduced stud or bearing 36 rockably engaging in an opening 37 formed in the inner wall 17 of the housing 13. The shaft 33 may be secured as by a pin 38 to the operator 32 and may be

secured to the operator 31 by means of a screw 39 which is threaded into the adjacent end of the shaft 33, as shown in Figure 4.

In order to provide a means whereby the bolt 20 may be releasably locked against rocking movement in an upward direction to a released position, I have provided a bolt locking lug 40 which is mounted on a shaft 41 carried by a bearing boss 42. The boss 42 extends inwardly from the inner wall 14 of the housing 12 and the locking lug 40 is preferably substantially rectangular in side elevation, as shown in Figure 1, so that the lower end of the lug 40 will substantially contact with the upper straight edge of the bolt 20. In this position of the locking lug 40, which is shown in dotted lines in Figure 1, the bolt 20 is held against upward rocking movement to a released position. The shaft 41 is extended outwardly through the inner wall 14, as shown in Figure 6, and a releasing button or operator 43 is secured as by a fastening member 44 to the extended end of the shaft 41.

The locking lug 40 is adapted to be resiliently held in either released or locked position by means of an elongated flat spring 45. The spring 45 is provided at one end thereof with an eye 46 engaging a pin 47 carried by the inner wall 14, and a spring tensioning pin 48 is also secured to the inner wall 14 in a position spaced from the pin 47 so as to force the spring 45 downwardly into engagement with the lug 40. The free end of the spring 45 is adapted to engage a selected side of the lug 40 depending on the position of the releasing button 43 and yieldably hold the lug 40 against turning movement.

The releasing button 43 is preferably disposed in only one of the housings shown in Figure 2 so that when the locking lug 40 is in locked position the operator 32 cannot be rocked so as to swing the bolt 20 to an upper released position. The bolt 20, when in locked position, is adapted to engage through an opening 58 formed in a keeper generally designated as 50. The keeper 50 comprises an inner plate 51 which is adapted to be secured as by fastening members 52 to the outer edge of the door 11. The plate 51 has extending outwardly therefrom a keeper housing including a forward wall 53, upper and lower walls 54 and 55, and opposite side walls 56 and 57. The walls 56 and 57 and the two walls 54 and 55 are spaced inwardly from the outer marginal edges of the plate 51 so that the fastening members 52 may be secured in position outwardly of the keeper housing or member 50. The keeper 50 includes an elongated slot 58 within which the hook 21 of the bolt 20 is adapted to engage and the opening 30 is of a size sufficient to permit the keeper housing 50 to engage within the escutcheon member 23, as shown in Figure 3.

Referring now to Figures 9, 10 and 11, there is disclosed a slightly modified form of this invention, the changes between the form shown in Figures 9, 10 and 11 being only with respect to the locking lug which is designated 40 in the preferred form of this invention. In other words, the form of invention shown in Figures 9, 10 and 11 includes a pair of housings 12a and 13a similar in every detail to the housings 12 and 13, and also includes a pair of operators for the door bolt 20a which are similar in every detail to the operators 31 and 32.

The inner wall 11a of the housing 13a is formed with a keyhole opening 59 which is selectively closed by means of a keyhole plate 60 pivotally

mounted on a pivot member 61. The bolt 20a is releasably held in locked position by means of a pivoted locking lug 62 which is mounted on a shaft 63 journaled through the inner wall 14a of the housing 12a. A lock releasing button or operator 40a is secured to the shaft 63 and is disposed interiorly of the housing 12a. The lug 62 comprises a polygonal body which is formed with flat faces 64 and 65 disposed on an obtuse angle relative to each other and also a flat face 66 disposed on an obtuse angle with respect to a flat face 66a positioned between the face 65 and the face 66. The lug 62 is formed with a key slot 67 extending inwardly from the edge 66 thereof, and preferably the lug 62 is formed with a cam-shaped member 68 extending from the edge 66.

The locking member 62 is yieldably held in either locked or released position by a longitudinally bowed spring 70 which is secured at one end thereof to a pin 71. A spring tensioning pin 72 engages the spring 70 between the ends thereof, and preferably, the spring 70 outwardly from the pin 72 is of substantially inverted V configuration so that the free end 73 thereof will be disposed in a position for engagement with either the flat face 64 or the flat face 65, depending on the relative position of the locking member 62. A key 74 may be inserted through the keyhole slot 59 when the locking member 62 is in a locking position and the key 74 then turned as shown in Figure 10 so as to engage in the key opening 67. This turning of the key 74 will swing the locking member 62 upwardly to the position shown in Figure 10 thereby positioning the flat face 66a in upwardly spaced relation with respect to the upper edge of the locking bolt 20a.

The bolt 20a may then be rocked upwardly by the handle 31a or a similar handle disposed in the housing 13a as described with respect to the bolt 20. The bolt 20 and the bolt 20a gravitantly move downwardly to a locked position, and the forward ends of these two bolts are formed with a cam 75 so that the bolt 20 will ride over the lower end of the keeper opening 58 and the hook 21 will then gravitantly drop downwardly with the bolt 20 on the inner side of the keeper 50 in a locked position, as shown in Figure 3.

This latch and bolt or lock is of simple construction and is so formed that it can be readily countersunk in the opposite sides of a sliding door as embodied in my co-pending application and the latch may be locked from the inside of the room by means of the locking member 40 which is operated by turning the operator 43 to a substantially horizontal locking position. Where a key is desired the locking member 62 may be used with the latch device as shown in Figures 9, 10 and 11, the key being extended through the outer housing 13a for engagement with the locking member 62.

What I claim is:

1. A door latch and lock comprising a pair of outwardly opening annular cup-shaped housings 65 adapted to be countersunk in opposite sides of a door with the inner walls of said housing spaced apart, an elongated door bolt disposed between said housings and extending horizontally therefrom, a pair of longitudinally arcuate operators 70 disposed one in each housing, a reduced diameter stud carried by each operator journaled in an inner wall, a polygonal shaft fixed to each of said operators and also fixed to said bolt whereby rocking of a selected operator will rock said bolt upwardly to released position, a locking lug for

said bolt, means pivotally supporting said lug from one of said housings above said bolt, an operator for said lug secured to said pivot means and disposed in the open side of said one housing, said lug having a pair of adjacent flat faces, and an elongated flat spring carried by said one housing engageable with one of said flat faces for holding said lug in either released or locked position.

2. A door latch and lock comprising a pair of outwardly opening annular cup-shaped housings adapted to be countersunk in opposite sides of a door with the inner walls of said housing spaced apart, an elongated door bolt disposed between said housings and extending horizontally therefrom, a pair of longitudinally arcuate operators disposed one in each housing, a reduced diameter stud carried by each operator journaled in

5 an inner wall, a shaft fixed to each of said operators and also fixed to said bolt whereby rocking of a selected operator will rock said bolt upwardly to released position, said shaft being polygonal in transverse section, a locking lug for said bolt, means pivotally supporting said lug from one of said housings above said bolt, an operator for said lug, said lug having a pair of adjacent flat faces, an elongated flat spring carried by said one housing engageable with one of said flat faces for holding said lug in either released or locked position, said lug having a key receiving slot extending inwardly from an edge thereof, and the other of said housings having a keyhole whereby a key may be extended through said other housing to swing said lug to a released position.

HARRY T. SMITH.
